Application September 22, 1944, Serial No. 555,269

19 Claims. (Cl. 33—79)

1

The present invention relates to drafting machines and similar devices comprising a parallel motion mechanism or arm, one end of which is secured to or is adapted to be secured to a table, drafting board or like device, affording a working surface over which the free end of the arm provided with some suitable instrument is adapted to be moved and the instrument carried thereby maintained parallel in successive positions.

Where the working surface is inclined, the parallel motion arm, which usually comprises two relatively movable sections, will not remain in any predetermined position without being held therein by the operator. In an attempt to overcome this difficulty, various counterpoise mechanisms have been proposed but none of the counterpoise mechanisms heretofore employed have been entirely satisfactory for various reasons, such as, that they give the machine a bulky and ungainly appearance, impose limitations upon the otherwise normal range of movement of the parallel motion arm, are not effective for all board angles, etc.

One of the principal objects of the present invention is the provision of a novel and improved drafting machine or similar device, including a parallel motion arm and counterpoise mechanism therefor, which machine is so constructed and arranged that it will be accurate in operation and will not have the appearance of being bulky and ungainly, and in which the counterpoise mechanism will not interfere with the otherwise normal range of movement of the parallel motion arm and will counterbalance or counterpoise the same in all positions.

Another object of the invention is the provision of a novel and improved drafting machine or like device comprising a parallel motion arm and counterpoise mechanism therefor effective to balance the parallel motion arm at all board angles from zero to ninety degrees.

Another object of the invention is the provision of a novel and improved drafting machine or like device comprising a parallel motion arm and counterpoise mechanism therefor, which counterpoise mechanism is automatically adjustable for different board angles.

Another object of the invention is the provision of a novel and improved drafting machine or like device comprising a parallel motion arm and counterpoise mechanism including a helical-type contractual spring for counterbalancing the parallel motion arm.

Another object of the invention is the provision of a novel and improved drafting machine or

2

similar device comprising a parallel motion arm and counterpoise mechanism therefor including a helical-type contractual spring adapted to be located at the side of the drafting board opposite the arm.

Another object of the invention is the provision of a novel and improved drafting machine or similar device comprising a parallel motion arm and counterpoise mechanism therefor including a helical-type contractual spring adapted to be located at the side of the drafting board opposite the arm, and means independent of the spring for varying the counterpoising effect thereof to balance the arm at different board angles.

15 Another object of the invention is the provision of a novel and improved drafting machine or similar device comprising a wheel and band type parallel motion arm and counterpoise mechanism for the parallel motion arm including a counterpoise force producing mechanism located underneath or behind the working surface or drafting board and connected to the arm by means permitting the arm to be adjusted angularly relative to the counterpoise force producing mechanism.

25 Another object of the invention is the provision of a novel and improved drafting machine or similar device comprising counterpoise mechanism for the parallel motion arm, which counterpoise mechanism includes a counterbalancing device,

30 such as a spring or weight located underneath or behind the drafting board or other working surface and connected to the arm by means comprising an eccentric or substantially eccentric cam and a lever interposed between the counterbalancing force producing device and the cam for changing the amount of counterpoising force applied to the arm so as to provide for different board angles.

Another object of the invention is the provision of a novel and improved drafting machine or similar device comprising a multi-section parallel motion arm of the wheel and band type and including means located at the side of the drawing board opposite the arm for counterbalancing the lower or instrument section of the arm independently of the bands of the parallel motion mechanism.

The invention resides in certain constructions and combinations and arrangements of parts and further objects and advantages will be apparent to those skilled in the art to which it relates from the following description of the preferred embodiment with reference to the accompanying drawings forming a part of this specification in which similar reference characters designate corresponding parts, and in which

Fig. 1 is a view of a drafting machine embodying the present invention attached to a Hamilton "Auto-shift" drafting table;

Fig. 2 is a fragmentary sectional view of the device shown in Fig. 1, approximately on the line 2—2 of Fig. 1, with both sections of the parallel motion arm positioned at right angles to the upper edge of the drawing board;

Fig. 3 is a fragmentary sectional view, with portions in elevation, approximately on the line 3—3 of Figs. 1 and 5, with the drafting board in a vertical position and the parallel motion arm in the position shown in Fig. 2;

Fig. 4 is a fragmentary sectional view approximately on the line 4—4 of Fig. 3; and

Fig. 5 is a fragmentary rear view of the device shown in Fig. 1, with the various parts in the positions shown in Fig. 3.

The drafting machine shown comprises a jointed two-section parallel motion mechanism or arm of the wheel and band type having an instrument or protractor head A at the free end and the other end fixedly secured, as by wood screws 10, to the drafting board B of a Hamilton "Auto-shift" drawing table, designated generally by the reference character C. The instrument head A is adapted to be moved about the working surface of the drawing board B and the rulers or other instruments forming a part thereof maintained parallel by the parallel motion mechanism in successive positions to which they are moved.

As previously stated, one of the objects of the present invention is the provision of a drafting machine comprising counterpoise mechanism effective to balance the parallel motion arm at all board angles without attention on the part of the operator as the drawing board is moved from one angle to another; therefore, the drawings show the drafting machine applied to an adjustable drawing board. The Hamilton "Auto-shift" drawing table referred to is of commercial construction and the drawing board B thereof can be readily located in either a horizontal or a vertical position or in any intermediate position. A complete description of the table is not necessary to a full understanding of the present invention. Suffice it to say that the drafting board B is pivotally connected, as by bolts 11, to vertical uprights 12 located adjacent to opposite ends of the table and vertically adjustable relative to the table proper by mechanism not shown but well-known in the art.

The parallel motion mechanism or arm shown, which is the preferred construction, comprises two angularly movable sections, each comprising a pair of wheels of equal diameter encircled by a flexible band and held in spaced relation with the band under tension by a strut so constructed as to enclose the band and wheels. The upper or anchor section of the parallel motion mechanism or arm comprises the wheels 13 and 14 encircled by an endless band 15 and held in spaced relation by a strut D comprising yokes or yoke members 16 and 17 connected by tubular side members 20 and 21. The upper yoke 16 is pivotally connected to the anchor assembly E, of which the upper wheel 13 is a part and through the medium of which the parallel motion arm is connected to the drawing board B by being fixedly secured to the upper or left-hand end of an elongated bolt or spindle 22 rotatably supported in the anchor bracket by anti-friction bearings 23 and 24, 25, 26 adjacent to the upper, intermediate and lower parts thereof, respectively. The

anchor bracket E is made in two parts 27, 28 to facilitate assembly of the various bearings and other parts. The endless band 15 is separable with the ends thereof adapted to be detachably connected together to facilitate assembly and replacement thereof. The tubular side members of the strut D are preferably similar to those disclosed and claimed in our copending application Serial No. 631,334 filed November 28, 1945, and are separable intermediate their ends with the adjacent portions thereof connected together by tube-like nut members rotatable in one direction to expand the strut and tense the band and in the opposite direction to release the same so that they can be moved along the side members to expose a portion or portions of the band.

The protractor section of the parallel motion arm is of similar construction and comprises equal diameter wheels 30 and 31 encircled by an endless band 32 and held in spaced relation by a strut comprising yoke members 33, 34 connected by tubular side members 35, 36 including tubular nut members similar to the tubular nut members previously referred to. The wheels 14 and 30 at the elbow of the arm are preferably formed integral and are operatively connected to the respective struts by anti-friction bearings 37, 38, respectively. The wheel 31 located at the free end of the parallel motion arm forms a part of the instrument head A. The construction of the protractor strut is such that it encloses the wheels and band of the protractor section.

The instrument A is similar in construction to that disclosed and claimed in our copending application Serial No. 555,268, filed September 22, 1944, entitled Drafting machine, and is not herein shown and described in detail. Reference is made to the aforesaid application for a complete disclosure thereof. Suffice it to say that the instrument head A comprises a ruler assembly F including a normally rotatable member 40 forming one element of the protractor proper and one or more rulers 41 detachably secured to a ruler or chuck arm 42. In addition to the aforementioned elements, the instrument head comprises a normally stationary protractor element 43, which cooperates with the rotatable protractor element previously referred to, to indicate the angular position of the ruler or rulers, index mechanism including the thumb piece 44, a protractor clamp 45, and a ruler assembly clamp 46.

The counterpoise mechanism shown comprises two helical-type contractual springs 50, 51 located behind or underneath the drawing board B for counterbalancing the anchor and protractor sections of the parallel motion arm, respectively. The contractual springs 50, 51 are pre-loaded at the time of assembly and are housed within a double-walled tubular member 52, the lower end of which is closed by a member 53 securely fixed to both tubes. The double-walled tubular member 52 extends generally in a direction at right angles to the upper edge of the drawing board and is pivotally connected to a bracket 54 through the medium of a member 55 fixed to the member 52 and pivotally connected to the bracket 54 by a pin 56. As shown, the bracket 54 is connected to the anchor bracket E by machine screws 57 and to the underside of the drawing board by wood screws 58. The construction is such that the tubular member 52 is supported underneath the drawing board B for rotation about the pin 56 as an axis, which axis is fixed with respect to the anchor bracket.

The purpose of the aforesaid pivotal construction will be hereinafter referred to.

The counterpoise springs 50, 51 are located between the inner and outer walls of the member 52 and are concentrically arranged with respect to each other with their upper ends abutting against the lower ends of two concentric members 60, 61, respectively. The upper ends of the members 60, 61 are provided with rollers 62, 63 continuously in contact with the lower or front sides of levers 64, 65, respectively. The lower or front ends of the members 60, 61 are provided with downwardly extending tubular members 66, 67, respectively, fixedly secured thereto. The tubular members 66, 67 extend between the counterpoise springs 50, 51 and in addition to forming guides for the members 60, 61 separate the springs, thus preventing one from interfering with the other. The upper ends of the tubes of the member 52 are flared towards each other in such a manner that the counterpoise springs will be retained therein even though the members 60, 61 and their respective tubes 66, 67 are withdrawn. This construction facilitates assembly as the counterpoise springs can be assembled with the member 52 prior to the assembly of the members 60, 61 therewith.

The levers 64, 65, previously referred to, are interposed between the rollers 62, 63, respectively, and ball bearing eccentric cams, designated generally by the reference characters 70, 71, which cams are similar to the ball bearing eccentric cams shown and described in our copending application Serial No. 555,267, filed September 22, 1944 and, as shown, comprise commercial ball bearings fixed to eccentrics 72, 73. The levers 64, 65 are pivotally connected to the anchor bracket E by a pin 74 fixed in said bracket to one side of the center of the spindle or bolt 22 and so located with respect to the eccentric cams that the levers extend generally parallel with the upper edge of the drawing board.

The lower or right-hand cam 70 which forms a part of the counterpoise mechanism for the anchor section of the parallel motion arm is keyed or otherwise non-rotatably fixed to the bolt 22 adjacent to its lower or right-hand end with its center offset from the center of the bolt 22 along the center line of the anchor section of the arm and in the direction in which the arm extends. The ball bearing eccentric cam 71 which forms a part of the counterpoise mechanism for the protractor or instrument section of the parallel motion arm is rotatably supported on the bolt 22 by an anti-friction bearing 75 with its center offset with respect to the center or axis of the bolt 22 in a direction generally parallel with the length of the instrument section or strut of the arm and to the side thereof corresponding to the direction in which the section extends from the elbow of the arm.

The eccentric cam 71 is operatively connected to the strut of the instrument section of the arm by a gear 76 fixed to a flange 77 formed integral with the eccentric 73 of the ball bearing eccentric cam 71. The gear and flange are concentric with the bolt 22 and the gear is continuously in mesh with a pinion 78 fixed to the lower end of a shaft 80 rotatably supported in the bracket E by anti-friction bearings 81, 82. The upper or left-hand end of the shaft 80 is provided with a pinion 83 continuously in mesh with an internal gear 84 fixed to the lower or right-hand side of a pulley 85 rotatably supported on the upper member 27 of the bracket E by an anti-friction

bearing 86. The pulley 85 is operatively connected to an equal diameter pulley 87 formed integral with or attached to the upper side of the yoke member 33 of the instrument strut by a cable 88 encircling both pulleys and provided with turnbuckles 89 for tensioning the same and adjusting the section angularly relative to the counterpoise mechanism proper, as will be hereinafter more specifically referred to. Preferably, the cable 88 is connected to the pulleys 85 and 87 by screws 90, thus reducing the amount of tension which would otherwise be necessary to prevent them from slipping on the pulleys. Any rotation of the instrument section of the parallel motion arm relative to the drafting board or any force tending to rotate the same is transmitted by the cable 88, pulley 85, etc., to the ball bearing eccentric cam 71.

The construction is such that when the parallel motion arm is at right angles to the upper edge of the drawing board, that is, in the position shown in Figs. 2, 3 and 4 of the drawings, the centers of the eccentrics 72, 73 are in line with the points of contact between the levers 64, 65 and the ball bearing cams 70, 71, respectively, and the center of the bolt 22, with the result that the forces of the counterpoise springs are applied in line with the center of the bolt 22 and the springs have no tendency to rotate the eccentrics 72, 73. As either section of the parallel motion arm is moved out of the aforesaid position, the eccentric associated therewith is rotated with it and its center moved to one side or the other of the center of the bolt 22 depending upon the direction in which the section is moved, with the result that the respective spring associated therewith tends to rotate the eccentric and thus counterbalance or counterpoise the section.

From the foregoing it will be apparent that for proper operation, a certain predetermined angular relationship must be maintained between the struts and the eccentric cams associated therewith. This does not present any particular problem in so far as the anchor strut is concerned because the desired angular relationship therebetween and the eccentric cam which forms a part of the connection between the strut and the counterpoise force producing mechanism can be readily effected at the time of assembly and with the construction shown the relationship thereafter remains fixed. However, because the connection between the protractor strut and the eccentric cam associated therewith includes the cable 88 which must be tightened at assembly and at various times thereafter, provision must be made for adjusting the angular relationship between the protractor or lower strut and its eccentric cam. In the present instance this adjustment is effected by the provision of the two turnbuckles 89, one in each of the two reaches of the cable 88. Without further description, it will be apparent that if only one turnbuckle was employed, the angular relationship between the strut and the eccentric cam would be changed every time the cable was tightened. However, once the desired relationship is obtained by turning one or the other of the turnbuckles, the cable can be tightened without disturbing the relationship by turning each turnbuckle an equal amount. Alternatively, other means may be provided for adjusting the angular relationship between the strut and the eccentric cam either at

the time of assembly or subsequent thereto, if desired.

Because different counterbalancing forces are required to balance the arm at any given position on the drawing board for different board angles, provision is made for changing the counterbalancing effect of the counterpoise springs as the board angle is changed. In the present instance this is accomplished without adjusting the springs or, in other words, independently of the springs by changing the point of application of the force of the springs to the levers 64, 65 interposed between the rollers 62, 63 and the ball bearing eccentric cams 70, 71. As shown, the point of application of the counterpoise spring pressures against the levers 64, 65 is varied in accordance with the board angle by moving the member 52 about the pin 56, previously referred to, as a pivot, thus moving the rollers 62, 63 along the levers 64, 65. The construction is such that the rollers 62, 63 can be located at any desired position along the levers 64, 65 intermediate a line through the pivot 74 or through the bolt 22.

Preferably the member 52 is moved automatically with a change in the board angle. As shown, this is accomplished by a roller 92 connected to the upper or front side of a lever 93 intermediate the ends of the lever, which roller engages within a cam slot 94 in the member 53. One end of the lever 93 is pivotally connected by a pin 95 to a projection on the bracket 54 and the other end thereof is pivotally connected by a pin 96 to the upper or rear end of a rod 97, the lower or front end of which rod is pivotally connected by a pin 98 to a bracket 99 fixed to a channel member 100 bolted to the uprights 12 and which channel member is a part of the "Auto-shift" table, previously referred to. The length of the rod 97 can be adjusted by a turnbuckle 101. In view of the fact that the force required to balance the parallel motion arm does not vary directly with the board angle, the slot 94 assumes the curved shape shown in the drawings when it is desired that the counterpoise mechanism balance the arm at all board angles between zero and ninety degrees. The shape can be computed by measuring the force required to counterbalance the arm at different board angles or by the cut-and-try method. The relative positions of the member 52, etc., when the board is in a vertical position, is that shown in full lines in Fig. 5. The relative positions of the various parts with the board in a horizontal position is shown in dot-dash lines and it will be understood that for intermediate board angles the parts will assume intermediate positions.

The following table gives approximately the counter-balancing force required for different board angles in percent of that required with the board in a vertical position.

Board Angle	Counterpoise Force
	Per cent
12°	20
15°	25
30°	50
45°	70
60°	87
70°	94
80°	100

While the preferred means for varying the counterpoising force at an accelerated rate relative to the rate at which the angle of the board is varied has been described with considerable

detail, it is to be understood that the present invention contemplates the use of means other than the curved slot construction shown.

As previously stated, the counterpoise springs are preloaded at the time of assembly and the construction employed permits the use of relatively heavy, substantially constant pressure springs, thus reducing the dimensional requirements of the device and making a more compact construction. The fact that the counterpoise springs are housed within the member 52 produces a very safe construction and one wherein the counterpoise mechanism is at least partially operable even though one or both of the counterpoise springs may break.

From the foregoing description of the preferred embodiments of the invention, it will be apparent that the objects heretofore enumerated and others have been accomplished and that a novel and improved drafting machine or like device has been provided comprising counterpoise mechanism of improved design and construction, which counterpoise mechanism does not interfere with the otherwise full movement of the parallel motion arm, does not give the device a bulky and ungainly appearance, is out of the way of the operator, and is effective throughout the range of movement of the parallel motion arm and for all different board angles.

While the preferred embodiments of the invention have been described with considerable detail, the invention is not limited to the particular construction shown and it is our intention to hereby cover all adaptations, modifications and uses thereof which come within the practice of those skilled in the art to which the invention relates and within the spirit and scope of the appended claims.

Having thus described our invention, what we claim is:

1. In a counterpoise mechanism for a drafting machine or like device including a parallel motion mechanism or arm adapted to be connected to a drawing board or the like for movement over at least a portion of one side thereof, a contractual helical spring located at the side of said drawing board opposite said arm for counterpoising said arm, and means automatically operable upon variation of the board angle for varying the counterpoising effect of said spring.

2. In a counterpoise mechanism for a drafting machine or like device including a parallel motion mechanism or arm adapted to be connected to a drawing board or the like for movement over at least a portion of one side thereof, a contractual helical spring located at the side of said drawing board opposite said arm for counterpoising said arm, and means automatically operable upon variation of the board angle for varying the counterpoising effect of said spring at an accelerated rate as said board angle increases.

3. In a counterpoise mechanism for a drafting machine or like device including a multi-section, parallel motion mechanism or arm adapted to be connected to a drawing board or the like for movement over at least a portion thereof, a contractual helical spring located at the side of said drawing board opposite said arm for counterbalancing a section of said arm, an eccentric cam, means adapted to operatively connect said eccentric cam to the section of said arm to be balanced by said spring, a lever interposed be-

tween said spring and said eccentric cam, means for pivotally supporting said lever at one side of said eccentric cam, and means for changing the point of application of the force of said spring to said lever.

4. In a counterpoise mechanism for a drafting machine or like device including a multi-section, parallel motion mechanism or arm adapted to be connected to a drawing board or the like for movement over at least a portion thereof, a contractual helical spring located at the side of said drawing board opposite said arm for counterpoising said arm, an eccentric cam, means for operatively connecting said eccentric cam to a section of said arm, a lever interposed between said spring and said eccentric cam, means for pivotally supporting said lever at one side of said cam, a member enclosing said spring, means for pivotally supporting said member, and means for rotating said member about said pivot for changing the point of application of the force of said spring to said lever.

5. In a counterpoise mechanism for a drafting machine or like device including a multi-section, parallel motion mechanism or arm adapted to be connected to a drawing board or the like for movement over at least a portion thereof, a contractual helical spring adapted to be located at the side of said drawing board opposite said arm for counterpoising a section of said arm, an eccentric cam, means for operatively connecting said eccentric cam to a section of said arm, a lever pivotally supported at one side of said eccentric cam and having a part thereof interposed between said spring and said cam, a member for enclosing said spring, means for pivotally supporting said member, and means actuated by a change in board angle for rotating said member to change the point of application of the force of said spring to said lever.

6. In a counterpoise mechanism for a drafting machine or like device including a multi-section, parallel motion mechanism or arm adapted to be connected to a drawing board or the like for movement over at least a portion of one side thereof, means comprising counterpoise force producing mechanism adapted to be located at the side of said drawing board opposite said parallel motion arm, and means including two internal gears located at opposite sides of the drawing board and connected by a shaft provided with pinions for operatively connecting said counterpoise force producing means with a section of said parallel motion arm to be counterbalanced thereby.

7. In a counterpoise mechanism for a drafting machine or like device, including a multi-section, wheel and band type, parallel motion mechanism or arm adapted to be connected to a drawing board or the like for movement over at least a portion of one side thereof, means comprising counterpoise force producing mechanism adapted to be located at the side of said drawing board opposite said parallel motion arm, means including two relatively rotatable members for operatively connecting said counterpoise force producing mechanism to a section of said parallel motion arm to be counterbalanced thereby, and means for adjusting said members angularly relative to each other.

8. In a counterpoise mechanism for a drafting machine or like device, including a multi-section, parallel motion mechanism or arm adapted to be connected to a drawing board or the like for

movement over at least a portion of one side thereof, a contractual helical spring adapted to be located at the side of the drawing board opposite said arm for counterpoising a section thereof, means including two relatively rotatable members

5 for operatively connecting said spring to the section of said parallel motion arm to be counterbalanced thereby, and means for adjusting said members angularly relative to each other.

10 9. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a strut rotatably supported concentric with said wheel, a second wheel spaced from said first wheel, means for pivotally connecting said second wheel 15 to said strut, a flexible band encircling said wheels, a third wheel concentric with said second wheel and fixed with respect thereto, a second strut, means for pivotally connecting said second strut to said third wheel for rotation about an axis concentric therewith, a fourth wheel spaced from said third wheel, means for pivotally connecting said fourth wheel to said second strut, a flexible band encircling said third and fourth wheels, a member located adjacent to said first 20 wheel, means for supporting said member for rotation about an axis concentric with the axis of said first strut, means for operatively connecting said member with said second strut, force producing means for counterpoising said second 25 strut and adapted to be located at the side of the drawing board opposite said wheels, and means for operatively connecting said force producing means to said member.

10. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a strut rotatably supported concentric with said wheel, a second wheel spaced from said first wheel, means for pivotally connecting said second wheel to said strut, a flexible band encircling said 30 wheels, a third wheel concentric with said second wheel and fixed with respect thereto, a second strut, means for pivotally connecting said second strut to said third wheel for rotation about an axis concentric therewith, a fourth wheel spaced from said third wheel, means for pivotally connecting said fourth wheel to said second strut, a flexible band encircling said third and fourth wheels, a member located adjacent to said first wheel, means for supporting said member for rotation about an axis concentric with the axis of said first strut, means for operatively connecting said member with said second strut, force producing means for counterpoising said second 35 strut and adapted to be located at the side of the drawing board opposite said wheels, and means for operatively connecting said force producing means to said member.

11. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a strut 40 rotatably supported concentric with said wheel,

11

at second wheel spaced from said first wheel, means for pivotally connecting said second wheel to said strut, a flexible band encircling said wheels, a third wheel concentric with said second wheel and fixed with respect thereto, a second strut, means for pivotally connecting said second strut to said third wheel for rotation about an axis concentric therewith, a fourth wheel spaced from said third wheel, means for pivotally connecting said fourth wheel to said second strut, a flexible band encircling said third and fourth wheels, a member located adjacent to said first wheel, means for supporting said member for rotation about an axis concentric with the axis of said first strut, means for operatively connecting said member with said second strut, force producing means for counterpoising said second strut and adapted to be located at the side of the drawing board opposite said wheels, means for operatively connecting said counterpoise force producing means to said member, and means for automatically changing the counterpoising effect of said force producing means upon a change of board angle.

12. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a strut rotatably supported concentric with said wheel, a second wheel spaced from said first wheel, means for pivotally connecting said second wheel to said strut, a flexible band encircling said wheels, a third wheel concentric with said second wheel and fixed with respect thereto, a second strut, means for pivotally connecting said second strut to said third wheel for rotation about an axis concentric therewith, a fourth wheel spaced from said third wheel, means for pivotally connecting said fourth wheel to said second strut, a flexible band encircling said third and fourth wheels, a fifth wheel located adjacent to said first wheel, means for supporting said fifth wheel for rotation about an axis concentric with the axis of said first strut, a sixth wheel concentric with said second and third wheels and fixed to said second strut, a flexible band encircling said fifth and sixth wheels, counterpoise force producing means for counterpoising said second strut and adapted to be located at the side of the drawing board opposite said wheels, and means for operatively connecting said counterpoise force producing means to said fifth wheel.

13. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a strut rotatably supported concentric with said wheel, a second wheel spaced from said first wheel, means for pivotally connecting said second wheel to said strut, a flexible band encircling said wheels, a third wheel concentric with said second wheel and fixed with respect thereto, a second strut, means for pivotally connecting said second strut to said third wheel for rotation about an axis concentric therewith, a fourth wheel spaced from said third wheel, means for pivotally connecting said fourth wheel to said second strut, a flexible band encircling said third and fourth wheels, a fifth wheel located adjacent to said first wheel, means for supporting said fifth wheel for rotation about an axis concentric with the axis of said second strut, a sixth wheel concentric with said fifth and sixth wheels and fixed to said second strut, a flexible band encircling said fifth and sixth wheels, counterpoise force producing means for counterpoising said second strut and adapted to be located at the side of the drawing board opposite said wheels, and means for operatively connecting said counterpoise force producing means to said fifth wheel.

14. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a strut rotatably supported concentric with said wheel, a second wheel spaced from said first wheel, means for pivotally connecting said second wheel to said strut, a flexible band encircling said wheels, a third wheel concentric with said second wheel and fixed with respect thereto, a second strut, means for pivotally connecting said second strut to said third wheel for rotation about an axis concentric therewith, a fourth wheel spaced from said third wheel, means for pivotally connecting said fourth wheel to said second strut, a flexible band encircling said third and fourth wheels, a fifth wheel located adjacent to said first wheel, means for supporting said fifth wheel for rotation about an axis concentric with the axis of said first strut, a sixth wheel concentric with said second and third wheels and fixed to said second strut, a flexible band encircling said fifth and sixth wheels, a spring for counterpoising said second strut adapted to be located at the side of the drawing board opposite said wheels, means for operatively connecting said spring to said fifth wheel, and means for automatically changing the counterpoising effect of said spring upon a change of board angle.

15. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a spindle rotatably supported in said anchor member concentric with said wheel and adapted to extend to opposite sides of the drawing board, a strut fixed with respect to said spindle, a second wheel spaced from said first wheel, means for pivotally connecting said second wheel to said strut, a flexible band encircling said wheels, a spring adapted to be located at the side of said drawing board opposite said wheels, means for operatively connecting said spring to said spindle, a third wheel concentric with said second wheel and fixed with respect thereto, a second strut, means for pivotally connecting said second strut to said third wheel for rotation about an axis concentric therewith, a fourth wheel spaced from said third wheel, means for pivotally connecting said fourth wheel to said second strut, a flexible band encircling said third and fourth wheels, a fifth wheel located adjacent to said first wheel, means for supporting said fifth wheel for rotation about an axis concentric with the axis of said spindle, a sixth wheel concentric with said second and third wheels and fixed to said second strut, a flexible band encircling said fifth and sixth wheels, a second spring located adjacent to said first spring, and means for automatically changing the counterpoising effect of said second spring upon a change of board angle.

and means for operatively connecting said second spring to said fifth wheel.

16. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a spindle rotatably supported in said anchor member concentric with said wheel and adapted to extend to opposite sides of the drawing board, a strut fixed with respect to said spindle, a second wheel spaced from said first wheel, means for pivotally connecting said second wheel to said strut, a flexible band encircling said wheels, a spring adapted to be located at the side of said drawing board opposite said wheels, means for operatively connecting said spring to said spindle, a third wheel concentric with said second wheel and fixed with respect thereto, a second strut, means for pivotally connecting said second strut to said third wheel for rotation about an axis concentric therewith, a fourth wheel spaced from said third wheel, means for pivotally connecting said fourth wheel to said second strut, a flexible band encircling said third and fourth wheels, a fifth wheel located adjacent to said first wheel, means for supporting said fifth wheel for rotation about an axis concentric with the axis of said spindle, a sixth wheel concentric with said second and third wheels and fixed to said second strut, a flexible band encircling said fifth and sixth wheels, a second spring located adjacent to said first spring, means for operatively connecting said second spring to said fifth wheel, and means for automatically changing the counterpoising effect of said springs upon a change of board angle.

17. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a spindle rotatably supported in said anchor member concentric with said wheel and adapted to extend to opposite sides of the drawing board, a strut fixed with respect to said spindle, a second wheel spaced from said first wheel, means for pivotally connecting said second wheel to said strut, a flexible band encircling said wheels, a cam operatively connected to said spindle and adapted to be located at the side of the drawing board opposite said wheels, a spring adapted to be located at the side of said drawing board opposite said wheels, means for operatively connecting said spring to said cam, a third wheel concentric with said second wheel and fixed with respect thereto, a second strut, means for pivotally connecting said second strut to said third wheel for rotation about an axis concentric therewith, a fourth wheel spaced from said third wheel, means for pivotally connecting said fourth wheel to said second strut, a flexible band encircling said third and fourth wheels, an instrument operatively connected to said fourth wheel, a fifth wheel located adjacent to said first wheel, means for supporting said fifth wheel for rotation about an axis concentric with the axis of said spindle, a sixth wheel concentric with said second and third wheels and fixed to said second strut, a flexible band encircling said fifth and sixth wheels, a second cam located adjacent to said first cam, means for supporting said second cam for rotation about an axis concentric with the axis of said spindle, means for operatively connecting said fifth wheel and said second cam whereby they rotate in predetermined relation upon rotation of either, a second spring located adjacent to said first spring, and means for operatively connecting said second spring to said second cam.

and sixth wheels, a second cam located adjacent to said first cam, means for supporting said second cam for rotation about an axis concentric with the axis of said spindle, means for operatively connecting said fifth wheel and said second cam whereby they rotate in predetermined relation upon rotation of either, a second spring located adjacent to said first spring, means for operatively connecting said second spring to said second cam, and means adapted to be operatively connected to the drawing board for automatically changing the counterpoising effect of said springs upon variation of the board angle.

18. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a spindle rotatably supported in said anchor member concentric with said wheel and adapted to extend to opposite sides of the drawing board, a strut fixed with respect to said spindle, a second wheel spaced from said first wheel, means for pivotally connecting said second wheel to said strut, a flexible band encircling said wheels, a cam operatively connected to said spindle and adapted to be located at the side of the drawing board opposite said wheels, a spring adapted to be located at the side of said drawing board opposite said wheels, means for operatively connecting said spring to said cam, a third wheel concentric with said second wheel and fixed with respect thereto, a second strut, means for pivotally connecting said second strut to said third wheel for rotation about an axis concentric therewith, a fourth wheel spaced from said third wheel, means for pivotally connecting said fourth wheel to said second strut, a flexible band encircling said third and fourth wheels, an instrument operatively connected to said fourth wheel, a fifth wheel located adjacent to said first wheel, means for supporting said fifth wheel for rotation about an axis concentric with the axis of said spindle, a sixth wheel concentric with said second and third wheels and fixed to said second strut, a flexible band encircling said fifth and sixth wheels, a second cam located adjacent to said first cam, means for supporting said second cam for rotation about an axis concentric with the axis of said spindle, means for operatively connecting said fifth wheel and said second cam whereby they rotate in predetermined relation upon rotation of either, a second spring located adjacent to said first spring, and means for operatively connecting said second spring to said second cam.

19. In a drafting machine or like device adapted to be used on an inclined drawing board or the like, an anchor member adapted to be connected to a drawing board or the like, a wheel fixed with respect to said anchor member and adapted to be located at one side of the drawing board to which the anchor member is attached, a spindle rotatably supported in said anchor member concentric with said wheel and adapted to extend to opposite sides of the drawing board, a strut fixed with respect to said spindle, a second wheel spaced from said first wheel, means for pivotally connecting said second wheel to said strut, a flexible band encircling said wheels, a cam operatively connected to said spindle and adapted to be located at the side of the drawing

15

board opposite said wheels, a compression spring adapted to be located at the side of said drawing board opposite said wheels, means for operatively connecting said spring to said cam comprising a lever pivotally supported at one side of said cam and operatively connected thereto, a third wheel concentric with said second wheel and fixed with respect thereto, a second strut, means for pivotally connecting said second strut to said third wheel for rotation about an axis concentric therewith, a fourth wheel spaced from said third wheel, means for pivotally connecting said fourth wheel to said second strut, a flexible band encircling said third and fourth wheels, an instrument operatively connected to said fourth wheel, a fifth wheel located adjacent to said first wheel, means for supporting said fifth wheel for rotation about an axis concentric with the axis of said spindle, a sixth wheel concentric with said second and third wheels and fixed to said second strut, a flexible band encircling said fifth and sixth wheels, means for adjusting said wheels angularly with respect to each other, a second cam located adjacent to said first cam, means for supporting said second cam for rotation about an axis concentric with the axis of said spindle, an internal gear fixed to said fifth wheel, a second internal gear fixed to said second cam, a second spindle rotatably supported in said anchor member and provided with pinion gears in mesh with said internal gears, a second compression spring located adjacent to said first spring,

16

means for operatively connecting said second spring to said second cam comprising a lever pivotally supported at one side of said second cam and operatively connected thereto, means for pivotally supporting said springs for rotation about an axis generally parallel with the axis of said spindle whereby the point of application of the force thereof to their respective levers may be varied, and means adapted to be operatively connected to the drawing board for automatically rotating said springs about said axis upon variation of the board angle for increasing the counterpoising effect of said springs at an accelerated rate as the board angle increases.
